UNITED STATES PATENT OFFICE.

JOHN SKELLY, ALLAN SKELLY, AND DAVID SKELLY, OF DUNASKIN,
SCOTLAND.

DEVICE FOR RAISING OR LOWERING WINDOW-BLINDS, SIGNAL-LAMPS, &c.

SPECIFICATION forming part of Letters Patent No. 636,296, dated November 7, 1899.

Application filed October 22, 1898. Serial No. 694,340. (No model.)

To all whom it may concern:

Be it known that we, JOHN SKELLY, colliery manager, ALLAN SKELLY, clerk, and DAVID SKELLY, timekeeper, citizens of the United 5 Kingdom of Great Britain and Ireland, and residents of 180 Lethanhill, by Dunaskin, in the county of Ayr, Scotland, have invented a new and useful Device for Raising or Lowering Window-Blinds, Signal-Lamps, and other 10 Articles, (which has been patented in Great Britain, No. 20,638, dated September 30, 1898,) of which the following is a specification.

The hereinafter-described invention refers to apparatus for raising and lowering window-blinds, signal-lamps, and other articles, and will be illustrated in its application to window-blinds only; but its adaptation for other purposes where articles are to be raised or lowered for the purpose of show will be readily 20 understood.

The object of the invention is to so construct such apparatus that the raising or lowering of the suspended window-blind will involve the expenditure of the minimum of time and 25 labor.

In the drawings, Figure 1 is a longitudinal section through one end portion of a curtain-roller provided with operating devices according to this invention. Fig. 2 is a front 30 view of the roller and curtain.

C is one end portion of a curtain or blind roller, the other end portion C' of which is journaled in any approved manner, as by a pin s, which runs in a bracket t on the window-frame X'.

A is the curtain or blind, wound upon the roller in the usual manner.

a is a tube slipped onto one end of the blind or winding roller and secured thereto 40 by screws or otherwise, these together forming the blind or winding roller, the tube a being closed at c and d by screw-threaded collars, each having a central hole in it in which a slotted hollow tube b is centered. This tube 45 b is fixed in a bracket e, carried either on the outside or inside surface of the window-stile

X. On the tube b a sliding collar g is strung and is free to move longitudinally of the tube b, being prevented from turning thereon by a pin h, which passes through the collar g 50 and through slots b' in the tube b, these slots being of such length as to allow the collar g a few inches of travel. A pulling-cord J' is secured to the pin h and passes through the tube b and over a pulley e' in the bracket e. 55 A screw-thread of quick pitch or a double or treble thread on the outer periphery of the collar g and a corresponding thread or threads is or are formed on the inner periphery of the tube a, so that when the collar g is pulled by 60 means of the cord J' to pull up the blind the outer tube a is caused to revolve and take up the blind, a very short travel of the pulling-cord being all that is necessary for raising the blind a number of feet. A spiral spring 65 i is situated between the fixed collar c and the sliding collar g to assist in the raising of the blind C or other article, the blind when freed so that it can drop falling by its own weight and compressing the spring i, so that its power 70 is stored to afterward assist the raising operation.

Having now described the invention, what we claim, and desire to secure by Letters Patent, is—

1. The combination, with a stationary tube, and a block slidable longitudinally on the said tube but not free to revolve thereon; of a revoluble winding-roller provided with a tubular end portion journaled concentric with the 80 said tube, said block and tubular portion being provided with engaging screw-threads, and means for moving the said block longitudinally arranged inside the said tube and connected with the said block, whereby the 85 roller is revolved, substantially as set forth.

2. The combination, with a stationary slotted tube, a block slidable on the said tube, and a pin secured to the said block and slidable longitudinally in the slotted tube and 90 preventing the said block from revolving; of a revoluble winding-roller provided with a tu-

5 bular end portion journaled concentric with the said tube, said block and tubular portion being provided with engaging screw-threads, an operating device secured to the said pin inside the said tube, and a spring assisting the longitudinal movement of the said block, said roller being revolved when the said block is slid longitudinally, substantially as set forth.

In witness whereof we have hereunto set 10 our hands in presence of two witnesses.

JOHN SKELLY.
ALLAN SKELLY.
DAVID SKELLY.
